UNITED STATES PATENT OFFICE.

CHRISTIAN CHRISTIANSEN, OF SIOUX FALLS, SOUTH DAKOTA, ASSIGNOR TO NEW WAY HARVESTER COMPANY, OF SIOUX FALLS, SOUTH DAKOTA.

SHOCKER.

Application filed October 13, 1922. Serial No. 594,319.

My invention relates to shocking machines of the type in which the receiver for the grain, hay or the like, is movable rearwardly from a shock forming platform and 5 opened at its rear side for dumping the shocks as they are completed. A machine of this character is disclosed in my U. S. Patents No. 1,295,271 of Feb. 25, 1919 and No. 1,413,966 of April 25, 1922.

10 In the last mentioned patented machine, the rear section of the receiver is moved upwardly to quite an extent before it is swung rearwardly for dumping the shock, and one object of the present invention is to provide 15 a novel form of locking means for holding the rear receiver section in operative relation with the front section, until said rear section has moved upwardly to a predetermined extent.

20 A further object of the invention is to provide unique means for guiding the rear receiver section as it swings rearwardly and upwardly in discharging the completed shocks.

25 In the patented machine above mentioned, it has been found that a great deal of undesirable friction exists between the shocks being formed and the cylindrical side wall of the receiver, as the grain or the like is 30 rotated within this wall. Hence, a further aim is to provide a vertical roller at the outer side of the aforesaid wall with its periphery exposed at the inner side of said wall, thereby engaging the grain as it is 35 being rotated and greatly relieving the friction.

In the patented machine to which I have referred, a packing roller was provided for packing the completed shocks before discharge, but it has been found that much better results can be obtained if this roller is positively driven instead of being turned merely by contact with the grain. A further object of the invention therefore is to 45 provide a novel mounting and driving means for this packing roller.

When the receiver moves rearwardly over the rotatable platform in discharging a completed shock, it is not desirable that either 50 the packing roller or the above mentioned vertical roller shall continue to rotate. A still further object of the invention therefore is to provide unique driving means for these rollers which will bring them to a

standstill when the receiver moves rearwardly to dumping position. 55

With the foregoing in view, the present invention resides in the novel subject matter hereinafter described and claimed, the description being supplemented by the accompanying drawings.

Figure 1 is a side elevation of the improved machine in shock-forming position.

Figure 2 is a view similar to Fig. 1 but illustrating the machine in shock dumping 65 position.

Figure 3 is a detail vertical sectional view showing the mounting and driving means of the friction relieving and grain packing rollers. 70

Figure 4 is a detail horizontal section on line 4—4 of Fig. 1, showing the driving means for the rollers in operative position.

Figure 5 is a duplicate of Fig. 4 with the exception that it illustrates the manner in 75 which the two units of the driving mechanism separate when the receiver moves rearwardly.

Figure 6 is a detail vertical section on line 6—6 of Fig. 3. 80

Figure 7 is a partial top plan with parts broken away and in horizontal section, showing more particularly the guiding rods for the rear section of the receiver.

Figure 8 is a detail vertical section of one 85 of the driving shafts for the packing roller.

Figure 9 is a fragmentary side elevation of the locking means for the rear section of the receiver.

Figure 10 is a horizontal section on line 90 10—10 of Fig. 9.

Figure 11 is a horizontal section on line 11—11 of Fig. 3.

In the drawings above briefly described, the numeral 1 designates the main wheeled frame of the machine, including a pair of parallel vertical side frames 2. The numeral 3 designates a rotatable platform whose rotating means may be substantially the same as in either of the patents above referred to or of other desired nature. 4 designates an upright cylindrical receiver which is normally disposed over said platform to receive grain or the like from an attached harvesting machine (not shown). Platform 3 is of course mounted on a central journal as in the above-named patents and its edge portion rests on supporting rollers R. The receiver 95 100 105

4 includes a front half section 5 having rollers 6 engaging upper and lower tracks 7 with which the side frames 2 are provided. An upwardly and rearwardly swinging rear half section 8 co-acts with the front section 5 in forming the complete receiver 4 and means are provided for bodily moving the two sections 5 and 8 rearwardly when a completed shock is to be dumped. During 10 this movement, rollers 9 on the rear receiver section 8 engage inclined tracks 10 carried by the frames 2, in the same manner as in Patent 1,413,966 thereby sliding the section 8 upwardly as it is moved rearwardly, prior 15 to upward and rearward swinging of said rear section which is effected by pushing of the front section against the same, as seen in Fig. 2.

For moving the receiver, any adequate 20 means may be provided. For instance, the arrangement which patent 1413966 shows for this purpose may be used, and the chain C and link L may be considered as parts of a similar arrangement.

25 In the preferred form of construction, the receiver is formed of sheet metal with angle iron or other reinforcements where desired and the front edges of the rear section 8 are reinforced by two angle metal bars 11 of this 30 frame and I make use of the outstanding flanges of these bars 11 to co-act with a pair of hook-shaped keepers 12 which are secured to the frame of the front receiver section 5, so as to normally hold the rear section 35 against outward swinging. This construction, while shown in a general way in the side elevation, is detailed in Figs. 9 and 10, from which views, it will be seen that the bills of the hook-like keepers 12 turn inwardly behind the flanges of the angle metal bars 11, when the rear receiver section 8 is closed, thus holding said section 8 against 40 accidental rearward swinging while a shock is being formed in the receiver. When this 45 section is raised however by co-action of the rollers 9 and tracks 10, the bars 11 withdraw from engagement with the keepers 12 when raised to a sufficient extent. Thus, the rear section 8 is free to be swung to the open position of Fig. 2 by the front section 5.

50 It is advisable to provide means for guiding the receiver section 8 as it swings rearwardly and upwardly and for this purpose, I have provided a pair of forwardly declined rods 13 whose front ends are pivoted to the frame of the front receiver section 5 adjacent the lower portion of this section, while the rear ends of said rods, when the receiver is in shock-forming position as seen 55 in Fig. 1, are supported by suitable guides 15 carried by the rear ends of the upper tracks 7. Thus, as the receiver 4 moves rearwardly, the rods 13 slide in the guides 15 and when the section 8 is swung rearwardly and 60 upwardly, its angle metal bars 11 slide along

the inner sides of the rods 13, so that there is no danger of striking the frame of the machine and interfering with proper operation of the rear receiver section.

For relieving the friction of the rotating body of grain against the annular wall of the receiver 4 when a shock is being formed, I provide a vertical roller 16 at the outer side of the receiver section 5, this section however being provided with a vertical slot 17 through which the periphery of the roller 16 is exposed at the inner side of the receiver wall. By positive means yet to be described, the roller 16 is rotated so as to inwardly pack the grain as it is being formed into a shock, so thereby easing the frictional contact thereof with the wall of the receiver.

For downwardly packing the upper end of a completed shock, I provide a conical packing roller 18 within the upper end of the receiver 4. In the present showing, this roller is of open work form and is secured to a shaft 19 which is rotatably held at one end in a substantial horizontal bearing 20, this bearing being pivoted at 21 to one of the frame members 22 of the front receiver section 5. This pivot permits the roller 18 to move vertically as the height of the shock increases and for properly guiding the roller and shaft 19 during this movement, the shaft is provided with a peripherally flanged guide roller 23 which is received between a pair of substantially upright guide rods 24 which rise rigidly from and are secured to the receiver section 5 in any desired manner.

The shaft 19 is provided with a bevel gear 25 meshing with a pinion 26 on the upper end of a vertically extensible flexible shaft 27 which at its lower end is connected with the uppermost journal 28 of the roller 16, the upper end of said shaft 27 being rotatable in a substantially vertical bearing 29 on the lower end of an arm 30 which depends from the bearing 20. The journal 28 is provided with a bevel gear 31 meshing with a similar gear 32 on a horizontal shaft 33 which is suitably mounted on the frame 22 of the front receiver section 5, said shaft 33 being provided with a bevel driving gear 34 normally meshing with a similar gear 35 on a transverse shaft 36 which is rotatably mounted at the front end of the frame 1, this shaft 36 being driven by any desired means (not shown).

From the arrangement above described, it will be seen that the rollers 16 and 18 are simultaneously rotated to properly act upon the grain being formed into a shock, but as soon as the receiver 4 is moved rearwardly towards its dumping position, the gear 34 moves out of mesh with the gear 35 and thus the two rollers which move rearwardly with the receiver, are brought to a standstill. At the same time, if desired, any suitable 130

provision may be made for discontinuing the rotation of the shaft 36, so that when the receiver is again moved forwardly after dumping the shock, the gears 34 and 35 may 5 easily intermesh, whereupon continued driving of the shaft 36 will take place.

From the foregoing taken in connection with the accompanying drawings, it will be seen that a number of substantial improvements have been made in the construction 10 of the patented machines. Excellent results have been obtained from these improvements in an actual working machine and hence they are preferably followed. It will be understood however that within the scope of 15 the invention as claimed, numerous minor changes may be made.

I claim:

1. In a grain shocker, the combination of 20 a rearwardly movable receiver having a rearwardly swinging rear section, means for lifting said rear section prior to swinging the same rearwardly, and means releasable by such lifting of said rear section for normally 25 holding this section in closed position.

2. In a grain shocker, the combination of 30 a rearwardly movable receiver having a front section and a rearwardly swinging rear section, means for lifting said rear section prior to swinging the same rearwardly, and a keeper carried fixedly by the front section 35 of said receiver and normally engaging said rear section to hold the latter against swinging, said rear section being movable out of engagement with said keeper when lifted in the above mentioned manner.

3. In a grain shocker, the combination of 40 a rearwardly movable receiver having a front section and a rearwardly swinging rear section, means for lifting said rear section prior to swinging the same rearwardly, vertical tracks carried by the sides of said rear section, and hooks carried by the sides 45 of the front section of the receiver, the bills of said hooks normally engaging said tracks to hold said rear section closed, said tracks being movable above said hooks when lifting of said rear section takes place.

4. In a grain shocker, the combination of 50 a frame structure having upstanding side frames, a rearwardly movable receiver mounted between said side frames and having a front section and a rearwardly and upwardly swinging rear section, a pair of 55 guides on the rear ends of said side frames at the upper portions thereof, and a pair of rods received slidably in said guides, said rods declining forwardly and being pivoted at their front ends to the front section of the 60 receiver, said rods forming guides for said rear receiver section during swinging of the latter.

5. The combination with a grain shocker 65 having an upstanding cylindrical receiver for the grain and a rotatable support for

rotating the grain in said receiver; of a vertical roller at the outer side of said receiver having its periphery exposed at the inner side of the latter to engage the grain, and means for driving said roller.

6. A shocker comprising a frame, a rotatably mounted platform on said frame, an upstanding receiver mounted on the frame over said platform and movable rearwardly for dumping, a vertical roller at the outer 70 side of and carried by said receiver, the periphery of said roller being exposed at the inner side of said receiver, and driving means for said roller formed of separable units carried by said frame and said receiver respectively.

7. A shocker comprising a frame, a rotatably mounted platform on said frame, an upstanding receiver mounted on the frame over 75 said platform and movable rearwardly for dumping, a vertical roller at the outer side of and carried by said receiver, the periphery of said roller being exposed at the inner side of said receiver, a horizontal shaft movable bodily with said receiver and geared to said 80 roller, said shaft having a driving gear, and a second driving gear normally meshed with the first named driving gear and carried by said frame, the two driving gears being separable when the receiver moves rearwardly.

8. The combination with a grain shocker including an upright cylindrical receiver for the grain, and a rotatable support for rotating the grain within said receiver; of a packing roller adapted to travel on the grain and mounted for vertical movement as the shock 90 is formed and means for positively driving said roller.

9. The combination with a shocker including a frame, a rotary platform thereon, and a rearwardly movable receiver carried by the frame over said platform; of a packing roller for the grain movable bodily with the receiver during its rearward movement, and driving means for said roller comprising 95 separable units carried by said frame and receiver respectively.

10. The combination with a shocker including a frame, a rotary platform thereon, and a rearwardly movable receiver carried by the frame over said platform; of a packing roller for the grain movable bodily with the receiver, a vertical shaft geared to said roller, a horizontal shaft geared to said vertical shaft and having a driving gear, the 115 two shafts being mounted for movement with the receiver, and a second driving gear mounted on said frame, said driving gears being separable when the receiver is moved rearwardly.

11. The combination with a grain shocker including an upright cylindrical receiver for the grain, a frame member spaced outwardly from said receiver, and a rotatable support for rotating the grain within the re- 120 125 130

ceiver; of a vertically swingable shaft connected with said frame member, a grain packing roller on said shaft, means for driving said roller, and parallel guides for guiding the vertical movement of said shaft.

12. The combination with a grain shucker including an upright cylindrical receiver for the grain, a frame member spaced outwardly from said receiver, and a rotatable support for rotating the grain within the receiver; of a substantially horizontal bearing pivoted to said frame member for vertical swinging and having a depending arm provided with a substantially vertical bearing, a substantially horizontal shaft having one end rotatably mounted in said substantially horizontal bearing, a packing roller on said shaft for the grain in the receiver, a vertically extensible drive shaft having its upper end received in said substantially vertical

bearing, and gearing for driving one shaft from the other.

13. A shucker comprising a frame, a rotatably mounted platform thereon, an upright cylindrical grain receiver carried by the frame over said platform and movable rearwardly to a dumping position, a vertical roller at the outer side of said receiver having its periphery exposed at the inner side of the latter, a packing roller at the upper end of the receiver for packing the grain therein, vertical shafting extending between the two rollers and operatively associated with both, and means for driving said vertical shafting including separable units, one of said units being movable with the receiver while the other unit is carried by the frame.

In testimony whereof I have hereunto affixed my signature.

CHRISTIAN CHRISTIANSEN.
